W. ROSENBERGER,
SANCTUARY OIL LAMP,
APPLICATION FILED DEC. 16, 1918.

1,345,960.

Patented July 6, 1920.

FIG. 2.

FIG. 3.

Wm Rosenberger ^{INVENTOR}
By ^{BY} *Ernest H. King* ^{ATTORNEY}

UNITED STATES PATENT OFFICE.

WILLIAM ROSENBERGER, OF SYRACUSE, NEW YORK, ASSIGNOR TO THE WILL & BAUMER COMPANY, OF SYRACUSE, NEW YORK, A CORPORATION OF NEW YORK.

SANCTUARY OIL-LAMP.

1,345,960.

Specification of Letters Patent.

Patented July 6, 1920.

Application filed December 16, 1918. Serial No. 266,898.

To all whom it may concern:

Be it known that I, WILLIAM ROSENBERGER, a citizen of the United States of America, and resident of Syracuse, in the 5 county of Onondaga, in the State of New York, have invented new and useful Improvements in Sanctuary Oil-Lamps, of which the following, taken in connection with the accompanying drawings, is a full, 10 clear, and exact description.

This invention relates to certain improvements in sanctuary oil lamps and refers more particularly to a means for holding 15 the wick in an upright position in the oil container.

These wicks are usually provided with a relatively small stiffening member of bamboo fiber, or equivalent combustible material running through the longitudinal center 20 of the wick to maintain all parts thereof in a substantially straight line, and to enable the wick to assume an upright position when supported at its lower end.

The main object of my present invention 25 is to provide simple and efficient means for gripping and releasing the lower end of the wick to hold it centrally in an upright position in the oil container and allowing it to be entirely consumed throughout its length 30 as the oil recedes in the container by combustion. At the same time to permit the wicks to be readily replaced in the same holder when desired.

In other words, I have sought to provide 35 a self contained wick holder capable of being readily inserted into and removed from the oil container with the wick therein and having a pair of spring jaws arranged and tensioned so as to grip the wick at 40 spaced points in its length, whereby said wick will be held more securely in an upright position when burning and, at the same time, may be easily and quickly released for removal, when necessary, by simply pressing the free ends of the jaws.

Other objects and uses relating to specific parts of the wick holder will be brought out 45 in the following description.

In the drawings—

50 Figure 1 is a vertical sectional view of a sanctuary oil lamp, embodying the features of my invention, the wick, spring jaws, and the supporting post for the jaws being shown in elevation.

Fig. 2 is a horizontal sectional view taken 55 in the plane of line 2—2, Fig. 1.

Fig. 3 is a sectional view similar to Fig. 2, showing a slightly modified form of wick-gripping device.

As shown in Fig. 1 the sanctuary oil lamp 60 comprises an oil container —1—, and a suitable wick holder consisting, in this instance, of the base —2—, having a central aperture —3—, therethrough, and an upstanding lifting rod or post —4—, rising from the 65 base at one side of the central aperture —3—, and opposed spring jaws 5 and 6 secured at one end to said post and extending diametrically across the upper face of base —2— for gripping the lower end of the 70 wick —7—, holding the latter in an upright position with its lower end extending through the aperture —3—, and its upper end extending to or above the level of the oil in the container —1—, and adapted 75 to be ignited for supplying the necessary light.

The base —2—, preferably consists of an inverted cup shaped plate of sheet metal, having its marginal flange as —8—, resting 80 upon the bottom of the receptacle —1—, portions of said flange being cut away or depressed inwardly to form lateral passages —9—, which permit the oil to pass therethrough beneath the base for saturating the 85 lower end of the wick and allowing said wick and oil in the container to be entirely consumed.

The central aperture —3—, in the base —2—, is of sufficient size to permit the lower 90 end of the wick to pass easily therethrough and may also serve to retain the adjacent portion of the wick in an upright position after it has burned below the level of the gripping jaws, 5 and 6.

The lifting rod or post —4—, preferably 95 consists of a piece of wire having its lower end put through an aperture as —10—, in the base —2—, some distance to one side of the central aperture —3—, and offset laterally at —11—, against the under side of said base where it is firmly held in position by solder —12—, said post being of sufficient length to extend above the upper end of the receptacle —1—, where it is provided 100 with an eye or handle —13—, by which the entire wick holder may be removed and replaced in and from the receptacle —1—.

The wick-gripping jaws 5 and 6, are secured at one end by solder 14, or equivalent fastening means to the post 4, in close proximity to the upper side of the base 2, and extend laterally or diametrically across the upper face of said base, and are tensioned to engage opposite faces of the wick 7, at different or spaced points in its length for assuring the retention of said wick in an upright position, and also permitting the wick to be released by simply compressing the free ends of the jaws against their own tension.

As illustrated, each jaw consists of a single piece of spring wire bent into U shaped form with its opposite arms one above the other, the arms of one of the jaws being spaced a sufficient distance apart to permit the other jaw to play between them.

Both jaws extend from the post 4, at one side of the wick some distance beyond the opposite side of said wick, and their intermediate portions which are adapted to engage the wick are off-set or depressed in opposite directions to form concave seats or gripping faces which engage opposite sides of the wick under the normal tension of the jaws, thus leaving the free ends of the jaws normally spaced apart, as shown in Fig. 2, to form handles which, when compressed serve to release the jaws from gripping engagement with the wick and permit the latter to be removed or replaced by a new one when necessary.

The construction of the jaws shown in Fig. 3 is very similar to those shown in Figs. 1 and 2, excepting that the base 2, is provided with an additional post 4' at the diametrically opposite side from the post 4, to which the adjacent end of one of the spring jaws is secured by solder 14' or other suitable means so that one of the jaws will be held at both ends while the other jaw is free to move under its own tension or under pressure of the finger.

By constructing the jaws in the manner described it will be seen that they engage the wick at different points in its length and that the points engaged are relatively narrow as compared with the total height of

the jaws, so as not to interfere with the free burning of the portion of the wick passing between the jaws which allows the entire wick to be consumed aided by the fact that the oil is allowed to flow beneath the base 55 for contact at the extreme lower end of said wick.

What I claim is:

1. A sanctuary oil lamp comprising in combination, an oil container, a wick-supporting base resting on the bottom of the container, and provided with a central aperture therethrough, a wick having its lower end inserted in said aperture and rising above the base, a lifting rod secured to the base at one side of the aperture, and a spring clip secured to said rod and provided with jaws tensioned to grip the wick at a point above the base to hold said wick in an upright position. 70

2. A wick-holder for sanctuary oil lamps comprising a base, adapted to rest upon the bottom of an oil container and provided with an upstanding lifting rod, and spring jaws mounted on the lifting rod and tensioned to grip an upstanding wick to hold it in an upright position while the wick is burning. 75

3. A wick-holder for sanctuary oil lamps comprising a base adapted to rest upon the bottom of an oil container and provided with an upstanding lifting rod, and spring jaws mounted on the lifting rod a short distance above the base and tensioned to grip an upstanding wick at spaced points 80 in its length for holding said wick in an upright position. 85

4. A wick-holder for sanctuary oil lamps comprising a base adapted to rest upon the bottom of an oil container and provided with an upstanding lifting rod at one side of its center and means on the lifting rod for holding a wick above the base. 90

In witness whereof I have hereunto set my hand this 3rd day of December 1918. 95

WILLIAM ROSENBERGER.
